UNITED STATES PATENT OFFICE.

JOHN E. LONGSTRETH, OF LANGSVILLE, OHIO.

AUTO JACK

Application filed July 26, 1924. Serial No. 728,453.

This invention relates to a jack mainly designed for use in connection with motor vehicles, the general object of the invention being to provide a jack of simple construction and which can be very easily operated and which has its handle part removable and formed to provide a number of tools for use in connection with a vehicle.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an elevation of the jack.

Figure 2 is a longitudinal sectional view therethrough.

Figure 3 is a section on line 3-3 of Figure 1.

Figure 4 is a transverse sectional view.

Figure 5 is a perspective view of the handle.

30 In these views, 1 indicates the outer or stationary member of the jack which is of hollow construction so that it can receive the inner or movable part 2. The part 1 is provided with the usual base 3 and it has one edge open to form a slot 4 and this edge carries a pair of rack members 5, one on each side of the slot 4. The member 2 is provided with the usual head 6 and it is formed with an opening 7, the upper wall of which is inclined, and wear pins 8 are inserted in recesses formed in said inclined upper wall. The handle 9 is provided with a head 10 of hammer shape and a trunnion pin 11 passes through the inner part of the head and is adapted to engage the recesses 45 in the rack members 5 so that the handle can be rocked to place the curved part of the head against the inclined wall of the member 2 or against the wear pins therein and thus lift the member 2 in the member 1. 50 A pin 13 is carried by a spring strip 14 which is fastened to one side of the member 1, as shown at 15, and this pin 13 is adapted to engage any one of a plurality of holes 16 formed in the member 2 to hold said member 2 in the position to which it has been moved by the handle member. The handle 55

member is then moved to the next higher pair of recesses in the rack members and is then tilted again to raise the member 2 another step. At the beginning of this raising movement the pin 13 will be forced out of the recess 16 due to the beveled construction of the parts, as shown at 17, and then the pin will engage the next lower recess 16 and thus hold the member 2 in its new position. The handle member 9 is then removed and placed in the next pair of recesses in the rack members and forced downwardly again to raise the member 2 another step and this will be kept up until the part being raised has been lifted to the proper position. As will be seen the pin 13 will hold the member 2 in the position to which it has been moved by the handle so as to permit the handle to be withdrawn and placed in a new pair of notches. To lower the jack the member 2 is slightly raised by the handle so that the pin 13 can be pulled from the recess 16 by the handle 18 on the strip 14 and then the handle is slowly moved upwardly to permit the member 2 to move downwardly until the pin 13 engages the next lower hole 16. Then the handle is placed in the next lower pair of recesses and the same operation repeated.

The handle 9 has its projecting part 12 shaped so that it can be used as a hammer and the handle is also provided with the openings 19 which may be used to receive nuts and the like so that the handle acts as a wrench when removed from the jack. The extremity of the handle is also beveled, as at 20, so that it can be used as a tire tool and for other purposes. 90

From the foregoing it will be seen that I have produced a simple and inexpensive jack and one which is very easy to operate and as a handle can be used as a hammer, a wrench and a tire tool, the device will be very useful when carried in a motor vehicle. 100

It is thought from the foregoing description that the advantages and novel features of my invention will be readily apparent.

I desire it to be understood that I may make changes in the construction and in the combination and arrangement of the several parts, provided that such changes fall within the scope of the appended claim. 105

What I claim is:—

A jack of the class described including a hollow standard having a slot therein, rack members at the sides of the slot, a member

having an opening therein slidably mounted in the hollow standard, the upper wall of the opening being inclined, wear pins positioned in said inclined wall, a handle, a trunnion pin passing through the same and engaging the rack members, a head on the handle having a curved part for engaging the wear pins in the inclined wall of the opening to actuate the sliding member when the handle is rocked on its pin, said sliding

member having a plurality of holes in one side thereof, a spring pressed pin on the standard for engaging with any one of said holes for holding the sliding member in the position to which it has been moved by the handle member so that said handle member can be placed in engagement with another tooth of each rack member. 15

In testimony whereof I affix my signature.
JOHN E. LONGSTRETH.
